United States Patent Office.

CHARLES ROSE, OF ALLENTOWN, PENNSYLVANIA.

Letters Patent No. 61,106, dated January 8, 1867.

IMPROVED CURTAIN-FIXTURE.

The Schedule referred to in these Letters Patent and making part of the same.

TO ALL WHOM IT MAY CONCERN:

Be it known that I, CHARLES ROSE, of Allentown, in the county of Lehigh, and in the State of Pennsylvania, have invented certain new and useful improvements in Window-Shade Fixtures; and do hereby declare that the following is a full, clear, and exact description thereof, reference being had to the accompanying drawings, and to the letters of reference marked thereon.

In the annexed drawings, making part of this specification, A represents the roller, (seen in end view, dotted line, Figure 1,) around which the curtain is wound. This roller is provided at one end with the usual disk or wheel C, which is perforated for screws to pass through to secure it to the roller, and also with a short shaft, for a bearing in the bracket, for that end. D represents a shaft provided with a disk; E, which is also perforated for the purpose of passing screws through to secure it to the roller. The outer end of this shaft is turned down smaller than the shaft itself, as seen at G, and has a thread cut upon the portion next to the shaft over which screw-thread a nut, H, passes. The periphery of this wheel or nut is provided with ratchet-teeth, as seen. F represents a disk, which is passed over the bearing G and is confined against the shoulder on shaft D, formed by turning down the arm or bearing G by means of the ratchet-nut H. An opening is made through shaft D, and a cord, J, has one of its ends passed through said opening and is there confined. K represents one of the brackets to support the roller, and pivoted to this bracket is a bent lever, I. This lever is provided with a ratchet-tooth, which catches into the wheel or nut H. L represents a spring, which is secured to the bracket K, and the end of which bears upon the lever I for the purpose of pressing it down upon the ratchet-nut H. M represents a cord, secured to the end of the lever I. By drawing down the cord M the lever I is raised off of the nut H. The arm G rests in a proper bearing or journal-box for it in the bracket K. The lower end of the curtain is weighted so that when the cord M is drawn down and the lever raised off of the nut the curtain will unwind and run down. The cord J winds around the shaft D in a different direction from that of the curtain on the roller, and the curtain may be wound up on the roller by drawing upon the said cord. It will thus be seen that by means of the two cords J and M the curtain can be wound up or unwound.

Having thus fully described my invention, what I claim as new, and desire to secure by Letters Patent, is—

The arrangement of the toothed nut H, the lever I and spring L with the disk F, shaft D, and roller A, the several parts being constructed and used as and for the purpose herein specified.

In testimony that I claim the foregoing, I have hereunto set my hand and seal this twenty-second day of October, 1866.

CHARLES ROSE.
